ROBERT C. RIDICK, OF KINGSTON, NEW YORK, AND ONE-THIRD TO CHARLOTTE
A. MAXWELL, OF SAUGERTIES, NEW YORK.

GAME APPARATUS.

1,382,695.

Specification of Letters Patent. Patented June 28, 1921.

Application filed January 5, 1920. Serial No. 349,409.

To all whom it may concern:

Be it known that I, CHARLES W. VAN VLEET, a citizen of the United States, and resident of Kingston, in the county of Ulster 5 and State of New York, have invented certain new and useful Improvements in Game Apparatus, of which the following is a specification.

This invention relates to a game apparatus; and it has for its object to provide a novel apparatus of simple and attractive construction and appearance whereby an 10 amusing game, requiring skill in its performance, can be played by any one, two or more persons.

The invention, generally stated, comprises a board having on its surface a devious course leading from a starting point to a goal, said course being defined by spaced-apart spots of various distinctive forms or values located at different relative positions in the course; a series of game-pieces adapted to be severally moved along said course and progressively upon certain predetermined spots thereof between the starting point and the goal; an indicating device adapted to be manipulated to determine the kind and the position of the spots upon which the game-pieces are to be periodically moved, and a projectile shooting device pivoted adjacent one side of said board and adapted to be manipulated to throw a pellet toward and against a game-piece located on said course.

The invention also comprises novel features of construction and arrangements of parts which will be hereinafter described and claimed.

In the drawings—

Figure 1 is a plan of a game-apparatus embodying my invention; the cover being removed.

Fig. 2 is a sectional elevation of the projectile shooting device, and the adjacent portion of the game-board on which it is pivotally mounted.

Fig. 3 is a perspective view of one of the game-pieces.

Fig. 4 is a similar view of the indicating device.

Referring to the drawings, 10 designates a board having upstanding side and end walls 11; the structure providing a shallow box or tray of proper shape and size for its intended purpose. A suitable lid or cover (not shown) for the structure may be provided. Upon the upper surface of the board is indicated a devious course leading from a starting station, as at 12, to a remote point, as at 13, constituting a goal. The course comprises a succession of spaced-apart spots 14 of various distinctive forms, or values, arranged in any suitable progressive order. In the present instance some of the spots are in the form of circles, others are diamond-shaped, and still others are star-shaped, as shown. The course, in the preferred form of my invention, is associated with a marine view, and is arranged to define a channel leading among a group of islands from a harbor (the starting point) to the open sea (the goal), the whole being lithographed or otherwise attractively illustrated upon the board or on a sheet of paper which is cemented to the board.

A series of game-pieces 15, preferably in semblance of boats, are provided, which pieces are adapted to be initially stationed in the harbor, and thereafter to be severally advanced, (if possible), along the spots of the course from the harbor to the open sea, by one of the players; the extent of each move of a boat being determined by the manipulation of a suitable indicating device. In the present instance, this device comprises a small cube 16 (Fig. 4), in semblance of a die, having upon its faces spots corresponding in form, or value, to those constituting the course; that is to say, two opposite faces are provided with stars, one face is provided with a diamond-shaped spot, and the remaining faces are provided with circular spots. In playing the game, this cube is thrown similarly to a die, the spot on the upper face indicating the particular move for the active game piece. Thus, if a circular spot be presented on the first throw of the cube, a boat is advanced from the harbor to the first circular spot of the course; if a star be presented then the boat is advanced to the first

star of the course; if a diamond be presented then the boat is advanced to the first diamond of the course. Likewise in succeeding plays the boat positioned on a spot is advanced to the next following spot of the course corresponding with the spot presented by the upper face of the cube when manipulated, and so on the boat is successively moved until it has reached the open sea, or 10 has been "sunk"; whereupon the play is repeated with succeeding boats.

As each boat is being advanced along the course, the opposing player (termed the "gunner") seeks to upset or "sink" it by 15 means of a projectile, such as a pellet of shot 17. In playing the game the boat is only fired on when it is located on a circle; the stars and diamonds being safety zones. The projectile shooting device, in its preferred form, is designed to be mounted at 20 the front of the board, the adjacent wall of which is preferably indented and formed in semblance of a "fort," as at 18, the construction of the shooting device being such that it may be trained to throw a projectile at a boat located on any spot throughout the length of the course. The shooting device, in its preferred form, comprises a base plate 19 having at one end an upstanding pintle 20 adapted to be pivotally supported in a vertically-perforated lug 21 at 25 the front of the board, so that the base plate and its appurtenances may be swung horizontally to various angular positions with 30 relation to the course on the board. Pivoted in and between a pair of lugs 22 on the base plate, adjacent the pivot 20, is a vibratory member 23 having a depending tail piece 24 and an upwardly and outwardly extending 35 arm 25. The latter bears at its free end a socket piece 26 adapted to receive the pellet 17. The tail piece 24 is adapted to be detachably engaged by a complementary upstanding lip 27 on the longer arm 28 of a 40 trigger lever which is pivoted in and between a pair of lugs 29 on the base plate adjacent the outer end of the latter. The co-operative relation of the parts just described is such that when the lip of the trigger lever 45 is engaged with the tail piece 24 of the member 23 the latter is held in position with the arm 25 extending outwardly and upwardly and the socket piece 26 forwardly and upwardly, as clearly indicated in Fig. 2. With 50 the parts thus positioned, if a pellet be inserted in the socket piece, and the shorter arm of the trigger lever be sharply depressed by pressure of the finger applied thereon, the engaged portion of the member 23 will 55 be quickly raised and the arm 25 thrown forward in a manner to project the pellet from the socket piece and toward a boat on a circular spot of the course, in accordance with the accuracy of the aim of the "gunner." 60 Such aim depends upon the angular relation 65

of the "gun" to the target and the amount of pressure applied by the player to the trigger; the proper throw and trajectory of the projectile in each case thus requiring a fair amount of skill and furnishing much amusement and entertainment. 70

According to the game one of the players manipulates the indicating device 16 and seeks to advance along the spots of the course to the open sea as many "boats" of the series 75 15 as possible, while his opponent on the other hand endeavors to "sink" them before they reach their ultimate goal. The players then change positions, and the previous gunner seeks to advance the boats to the goal while 80 his opponent in turn aims to sink them. The player who succeeds in getting the larger number of boats to the open sea is the 85 winner.

It is to be understood that the game may 85 be conducted with the view of one or the other players advancing a certain number of boats safely along the course in a given time and in a certain sequence; and in other respects various interesting modes of procedure may be adopted and followed at the pleasure of the players. 90

I do not limit my invention to the specific details and features of construction herein disclosed as the same may be modified within the principle of my invention and the 95 scope of the appended claims.

I claim:

1. A game apparatus comprising a board having a course indicated on its surface by 100 a succession of spots of various designations, said course leading deviously from a starting point to a goal, a position indicating device, a series of game-pieces severally movable along said course and upon certain 105 spots as determined by the manipulation of the indicating device, and a projectile shooting device pivotally mounted adjacent one side of said board and adapted to be manipulated to shoot a projectile toward a game-piece located on said course. 110

2. A game apparatus comprising a board having a devious course thereon defined by a succession of spots of various designations at different points of the course, a cube-member having facial indications thereon corresponding with said designations, a series of game-pieces severally movable along said course and upon certain spots as determined by the manipulation of the cube-member, and a projectile shooting device pivotally mounted adjacent one side of said board and adapted to be manipulated to shoot a projectile toward a game-piece located on said course. 115 120

3. A game apparatus comprising a board having a devious course thereon leading from a starting station to a goal, said course being defined by spaced spots of various distinctive forms, a block having a plurality 130

of faces bearing spots corresponding in form with those of the course, a series of game-pieces severally movable along said course and progressively upon certain spots determined upon by manipulation of the block, and a projectile shooting device pivoted adjacent one side of said board and adapted to

be manipulated to throw a pellet toward a game-piece located on said course.

Signed at Kingston, in the county of Ulster and State of New York, this 2d day of January, A. D. 1920.

CHARLES W. VAN VLEET.
